UNITED STATES PATENT OFFICE.

WILLIAM ANDREW HATCHER, OF DALLAS, TEXAS, ASSIGNOR OF ONE-FOURTH TO M. W. KEENE, OF SAME PLACE.

FURNACE.

SPECIFICATION forming part of Letters Patent No. 445,249, dated January 27, 1891.

Application filed April 15, 1890. Serial No. 348,072. (No model.)

To all whom it may concern:

Be it known that I, WILLIAM ANDREW HATCHER, a citizen of Dallas, in the county of Dallas and State of Texas, have invented 5 certain new and useful Improvements in Furnaces; and I do hereby declare the following to be a full, clear, and exact description of the invention, such as will enable others skilled in the art to which it appertains to 10 make and use the same.

My invention relates to an improvement in furnaces, and more particularly to such as are employed for burning offal, refuse from 15 slaughtering-houses, &c., and has for its object to construct a furnace in such a manner that the requisite amount of heat may be employed without the liability of destroying any 20 part of the furnace.

A further object is to so construct a furnace for burning refuse, &c., that the materials inserted therein may be consumed, and any liquid matter be vaporized and discharged 25 in the form of vapor.

A further object is to produce a furnace 30 for burning refuse, &c., in which the chamber for containing the material to be consumed shall be surrounded by water.

A further object is to so construct a furnace 35 to be used in connection with slaughtering-establishments for burning offal, &c., that the chamber in which the offal is to be consumed shall be surrounded with water, and a sufficient amount of steam generated by the engine of such slaughtering-establishment or 40 other machinery.

With these objects in view the invention 45 consists in certain novel features of construction and combinations and arrangements of parts, as hereinafter set forth, and pointed out in the claims.

In the accompanying drawings, Figure 1 is 50 a front view of the furnace. Fig. 2 is a longitudinal sectional view. Figs. 3 and 4 are views of certain details.

A represents the front portion of the furnace, made of suitable material and containing 55 a fire-box B, grate C, and ash-pit D, suitable doors B' and D' being provided for the fire-box and ash-pit, respectively, and above the door B' a stoke-hole B² is made.

Located in and surrounded by the brick-

work of the furnace in rear of the fire-box is a boiler F, having a large flue G communicating at its front end with the fire-box of the furnace. The outer and inner shells a b of 55 the boiler are closed by means of heads c d, one at each end, each of said heads being provided with flanges c', which enter the ends of the boiler, and these flanges are secured to the shells a b by means of rivets c² or in any 60 other suitable manner. The inner and outer shells a b are so arranged relatively to each other that the water-space at the upper portion of the boiler will be greater than the space at the lower portion of said boiler, as 65 shown in Figs. 1 and 2. At one end of the boiler a space e is made, with which space an opening e' in the rear end of the boiler is made to communicate, by means of which opening access may be had to the interior of the boiler. The opening e' is normally closed by 70 means of a cover H, connected at one end of a screw-threaded rod f, the other end of said rod being passed through a screw-threaded perforation in a yoke f', secured to the rear 75 head d of the boiler and prevented from working loose by means of a nut d². Below the cover H the masonry is arched concentric with the boiler, as shown in Fig. 2, and beneath this arch an opening g is made in the 80 rear wall of the furnace, through which an implement may be inserted for agitating the materials in the flue of the boiler, such materials being introduced into said flue in a manner presently explained.

In the upper part of the boiler the two shells a b are provided with openings h, the opening in the outer shell a being made larger than the opening in the inner shell b. Secured to the outer shell a and surrounding 85 each opening h therein is an annular sleeve i, which extends upwardly through the masonry on top the boiler to the top surface thereof. A similar annular sleeve i', of smaller diameter, is secured to the inner shell b and 90 adapted to surround each perforation therein, these sleeves i' also extending upwardly to the top of the masonry over the boiler. The chambers i², formed by the sleeves i i', are closed by annular plates i³, which plates are 95 provided with inwardly-projecting flanges, by means of which they are riveted or other-

wise secured to the sleeves *i i'*. Thus it will be seen that the flue *G* in the boiler *F* is provided with openings or mouths *H'*, through which material may be inserted into said flue. 5 The inlets or mouths *H'* are covered by means of lids *H²* of fire-clay or other suitable material, having handles *H³* secured thereto by means of which to remove and replace them.

10 Beneath the boiler and extending beyond the rear end thereof a chamber *I* is formed between said boiler and the masonry at the base of the furnace. The chamber *I* is adapted to communicate with the flue *G* of the boiler at the rear end thereof, as shown in Fig. 2, and also by means of perforations *j*, made through the shells *a b* at the lower portion of the boiler. These perforations *j* are preferably arranged in two series, as shown 15 in Fig. 2, each series extending from end to end of the boiler, or nearly so. In producing the perforations *j* the shells *a b* are provided with aligned screw-threaded perforations, and in each pair of these aligned perforations a 20 section of pipe *j'* is screwed and riveted in any suitable manner.

Communicating with the chamber *I* at the forward end and at opposite sides thereof are two flues *J J*, which flues extend in a diagonal direction to the top of the furnace at the forward end thereof. The two flues *J* communicate at their upper ends with a common chamber *J'*, which chamber in turn communicates with a stack *J²*.

35 Fire having been built in the fire-box, and the boiler having been filled with water, the offal, refuse, or other material is introduced into the flue *G* through the mouths *H'*, any liquid introduced with such material finding 40 its way through the perforations *j* into the chamber *I*. The heat from the fire passes from the fire-box through the flue *G* and acts on the material contained therein. From the flue *G* the heat passes into and through the 45 chamber *I*, and finally out through the flues *J* to the stack *J²*. During the passage of the heat through the flue *G* the material therein will be consumed, and during its passage through the chamber *I* the gases will be consumed and the liquid in said chamber will be 50 vaporized.

By constructing and arranging a furnace for burning offal, &c., as above described, the boiler will be protected by the masonry surrounding it, and a great heat may be employed for burning refuse, &c.

55 My improved furnace is admirably adapted for use at a sanitary crematory where garbage and city offals are burned in connection with 60 a slaughtering-establishment, and the steam generated may be employed for running necessary machinery.

Having fully described my invention, what I claim as new, and desire to secure by Letters 65 Patent, is—

1. In a furnace, the combination, with suit-

able masonry having a fire-box built therein, of a boiler inclosed by said masonry and having a flue in communication with said fire-box, and means for introducing material into 70 said flue, substantially as set forth.

2. In a furnace, the combination, with a fire-box, of a boiler having a flue therein, said boiler having mouths or openings communicating with said flues, and a chamber beneath 75 the boiler and communicating with the flue in the boiler, substantially as set forth.

3. In a furnace, the combination, with a fire box, of a boiler having a flue in communication with said fire-box, said boiler being provided with openings or mouths in its upper portion and flues or passages in its lower portion in communication with the flue in the boiler, and a chamber beneath the boiler, substantially as set forth. 80

4. In a furnace, the combination, with a fire-box, of a boiler having a flue in communication with said fire-box, said boiler being provided with mouths which extend to the top of the furnace and communicate with the flue 90 in the boiler, lids for said mouths, and a chamber beneath the boiler, in communication with the flue therein, substantially as set forth.

5. In a furnace, the combination, with a fire-box, of a boiler having a flue in communication with said fire-box, said boiler being provided with openings in its upper portion, sleeves secured to and surrounding said openings and extending to the top of the furnace, 95 lids adapted to cover said sleeves, and a chamber beneath the boiler, in communication with the flue in the boiler, substantially as set forth.

6. In a furnace, the combination, with a fire-box, of a boiler having a flue in communication with said fire-box, said boiler being provided with openings in its upper and lower portions, which communicate with the flue in the boiler, a chamber beneath the boiler, in communication with the flue therein, and flues connecting said chamber with a smoke-stack, 100 substantially as set forth.

7. In a furnace, the combination, with a fire-box, of a boiler having a flue in communication with said fire-box, said boiler being provided with openings in its upper and lower portions, which communicate with the flue in said boiler, a chamber beneath the boiler, and flues communicating at one end with said chamber at opposite sides of the boiler and at their other ends in a common smoke-stack, 115 substantially as set forth.

8. In a furnace, the combination, with suitable inclosing masonry and a fire-box, of a boiler having a flue in communication with said fire-box, said boiler having openings or mouths in communication with the flue therein, the boiler also having an opening in one end, a valve or door for closing said opening, a chamber beneath the boiler, and flues connecting said valve with the open air, substantially as set forth. 125

9. In a furnace, the combination, with suit-

able inclosing masonry and a fire-box, of a boiler having a flue in communication therewith, mouths in said boiler in communication with said flue, a chamber beneath the boiler, 5 in communication with the flue in the boiler, said masonry being provided with an opening in one end of the furnace, by means of which access may be had to the flue in the boiler, substantially as set forth.

10. 10. In a furnace, the combination, with a fire-box, of a boiler having a flue in communication therewith, said boiler comprising two shells arranged eccentrically one within the other, said shells being provided with open-

ings in their upper and lower portions, sleeves 15 connected to the tops of said shells and surrounding the openings to produce mouths communicating with the flue in the boiler, flues inserted in the openings in the lower portion of the shells, and a chamber beneath 20 the boiler, substantially as set forth.

In testimony whereof I have signed this specification in the presence of two subscribing witnesses.

WILLIAM ANDREW HATCHER.
